Dec. 1903

Henry G. Morris of Philadelphia, Penn.
Letters Patent No. 7903 Dated Feb. 28th 1864.
Design for Stop-cock.

The schedule referred to in these Letters Patent and making part of the same.

To all whom it may concern:

Be it known that I, Henry G. Morris, of Philadelphia, in the County of Philadelphia and State of Pennsylvania, have originated and designed a new pattern of Steam, Water or Gas Cock, of which the following is a full, clear and exact description reference being had to the accompanying drawings and photograph making part of this specification.

In the drawings, figures 6 and 8 represent top and side views of a cock, and on the photograph, Figure 1, shows a perspective view of a cock.

Claim.

What I claim as my invention, and desire to secure by Letters Patent is, the design or pattern of Steam, Water, or Gas Cock as herein set forth.
